ACOUSTIC CAP FOR STACKS

Robert B. Jacobs, Homewood, and Irwin Ginsburgh, Chicago, Ill., assignors to Standard Oil Company, Chicago, Ill., a corporation of Indiana

Application June 29, 1955, Serial No. 518,742

5 Claims. (Cl. 181—50)

This invention relates to reducing noise on stacks and, more particularly, is concerned with an apparatus for reducing noise when exhausting high pressure gases which contain erosive solids suspended therein.

In many modern petroleum refineries it is desired to conduct operations wherein exhaust gases are vented from high pressure chambers wherein the vented gases have contacted a bed of fluidized finely divided solids. Solids from such operations remain entrained in the exhaust gases and these solids erode stack silencers heretofore available with the result that frequent and costly repairs are necessary. Many types of silencers have been designed and attempted for use on this difficult duty but heretofore none has been satisfactory from the standpoints of noise attenuation, erosion resistance, and ease of replaceability when necessary.

It is, therefore, an important object of our invention to provide a stack silencer which is of rugged and simple construction making for easy fabrication and replacement. An additional object of our invention is to provide an apparatus which is particularly effective on the venting of gases containing finely divided or entrained solids. A further object is to provide an apparatus which is effective in noise attenuation over a wide range of frequencies. Still another object of our invention is to provide an effective stack silencer which is not affected by erosion.

Although the invention is primarily directed toward the solution of a serious problem in connection with the venting of gases from petroleum refining equipment, an object of the invention is to provide a type of stack silencer which will be generally useful for controlling the flow of fluids and reducing the noise thereof, particularly when said fluids contain erosive solids. A more specific object of the invention is to provide a method and means for reducing or eliminating the noise of flue gases from a catalyst regenerator outlet pipe. These and other objects of our invention will become apparent as our description thereof proceeds.

Briefly, we attain the objects of our invention by providing an acoustic cap which comprises a sleeve which is mounted about the upper end of a stack and spaced therefrom to provide an annular chamber, the lower end of the annular chamber being closed by a bottom closure plate. A plurality of gas ports in the portion of the wall of the stack enclosed by the sleeve discharge into the annular chamber. Across the flow area of the stack above the ports, we provide a cap plate which supports a perforated support containing a quantity of a sound-absorbing refractory fiber. This produces a cylindrical chamber closed at its upper end. The height of such chamber above the ports and below the cap is such that the travel of any finely divided solids entrained by the stack gases will be spent and the solids will fall back or settle within the quiescent fallout chamber at the closed upper end of the stack. The separated or settling solids are resuspended in a subsequent flow of gases which issue laterally from the ports and then upwardly within the annular chamber. This results in a minimum of erosion due to impingement

2

of entrained solids while maintaining the full acoustic efficiency of the cap plate.

The walls of the annular chamber, as well as the floor thereof, are provided with a sound-absorbing refractory lining. Similarly, the stack itself may be lined, such linings serving further to reduce stack noises. The ports and annular chamber through which the gases vent may be streamlined to prevent the generation of sound during the venting of the gases from the stack through the lateral ports.

10 To illustrate our invention, we will describe embodiments thereof which may be applied to stacks on fluidized catalyst systems. In the operation of fluid catalyst processes, it may be necessary to regenerate or otherwise treat the catalyst in a large body by blowing gases therethrough and venting the gases to the atmosphere. Because of the fine state of subdivision of the catalyst, considerable quantities of the catalyst may be carried from the contacting chamber with the waste gases. Because of the large volume of gases, it has been a difficult problem to devise a throttling means which will effectively reduce the pressure from the contacting pressure to the pressure of the atmosphere without generation of objectionable noise and without serious erosion of the equipment.

15 Various types of throttling valves have been tried for the purpose and, although it is possible to throttle the gases to atmospheric pressure with a tolerable erosion of the throttling valves by the entrained solids, the design of such throttling valves have inherently generated excessive sound. However, our acoustic cap construction makes possible the use of such throttling valves within the stack and permits the venting of the stack gases to the atmosphere without attaining the objectionable level of noise customarily associated with such venting.

20 25 30 35 Further details of the construction and advantages of our atmospheric cap will be described in connection with preferred embodiments thereof which are illustrated in the drawings and wherein:

Figure 1 is an elevation of our cap, partly in section; Figure 2 is a section taken along the line 2—2 in Figure 40 1; Figure 3 illustrates a modification of the cap shown in Figure 1; and Figure 4 is a section taken along the line 4—4 in Figure 3.

45 50 55 Referring to the drawings, the stack 10, provided with the conventional refractory lining 11, is provided with ports 12 in the wall of the stack 10 at the upper end 10a thereof. At vertically spaced points in the stack 10 we provide conventional fixed orifice throttle plates which, since they do not form a part of the present invention, are not shown in the drawings. However, many such throttle plates or valves are available for this duty and can readily be supplied by those skilled in the art. These are all characterized, however, by generating sound which we reduce by means of our acoustic cap.

60 65 70 The member 10a, which if desired may comprise a separate cylindrical extension of the stack 10, is closed at its upper end by a circular plate 13 and supported therein, for example, by cross members or beams 14. A perforated support 15 is held to plate 13 by bolts 16, the support 15 confining a mass 17 of sound-absorbing refractory fiber such as glass or asbestos wool.

An outer housing or sleeve 18, supported on annular 65 70 bottom closure plate 19, surrounds the cylindrical member 10a and forms the annular chamber 20 which is provided with sound-absorbing lining 21 on both walls. A fire-brick floor 22 or other sound absorber is provided in the base of the annular chamber 20 to absorb further sound which comes through the ports 12. A safety screen 23, supported on frame-work 24, is carried by the top of

the unit to retain large objects which might otherwise be ejected from the stack.

In operation, the flue or stack gases with entrained solids flow upwardly within stack 10 generating entrained sound in passing through the throttle zones. On reaching the ports 12, the solids tend to continue upwardly beyond them and their erosive energy is spent within the quiescent fall-out or settling zone 25. The pad 17 is placed a distance of at least 3 feet above the ports 12 with a flow rate of exhaust gases of less than about 100 feet per second. The gases pass through the ports 12 into annular sound-absorbing chamber 20, and the entrained sound is absorbed by the pad 17 in the top of the solids-separating zone 25. In so doing, finely divided solids, which fall downwardly within the zone 25, are resuspended in a subsequent flow of gas and carried through the ports 12. The sound-absorbing and abrasion-resistant lining 21 on the concentric walls of the chamber 20 minimize and reduce noise generated in the throttle zones and not absorbed by the sound-absorbing pad 17, or noise generated by the flow of gases through the ports 12 will be absorbed by the lining 21 before discharge to the atmosphere.

In Figures 3 and 4, further design modifications are illustrated for reducing the entrained sound which reaches the annular chamber 20. This may be accomplished by providing a plurality of radially-extending partitions 26. Each partition comprises a pair of perforated plates 27 and 28 with a sound-absorbing layer 29 therebetween. The bottom of the annular space confined by the adjacent pairs of partitions 26 is filled with a refractory cement 31 and formed in a streamlined fashion so as to reduce to a minimum the generation of noise by the gases in issuing from the ports 12. Further, the flow area of the ports 12 and of the streamlined sound-absorbing chambers 30 is designed to be at least equal to the flow area in section 10a.

The blanked-off portion 38 of the annular chamber 30 between adjacent ports 12 may be provided with reinforcing or support plates 39 which extend between the inner cylinder 10a and the outer cylinder 18. A number of top cover plates 40 complete the enclosure of the blanked-off section 38. These are removable so that the sound-absorbing material 29 (whether it be such as firebrick or special cement) can be readily replaced.

In a typical installation, the stack may have an internal diameter of about 5 feet with an abrasion-resistant refractory cement lining 21 about 1.5 inches thick. The sound-absorbing pad 17 is at least about 6 feet above the upper edges of the ports 12, each port 12 representing an opening about 21 inches wide and about 3 feet, 4.5 inches high. The top and side edges of the ports 12 may be re-enforced by cut sections 33 of 3-inch pipe to provide a streamlined opening 12.

The silencer or sound-absorbing sleeve 18 may suitably have an internal diameter of about 8 feet, 8 inches providing, after application of 1.5 inch thick linings 21, an annular chamber 30 between member 10a and sleeve 18 which is about 20 inches wide. Access to the sound-absorbing chamber 30 may be had through the sleeve 18 by means of removable plate 40 and secured thereto by conventional means.

The sound-absorbing pad 17 may comprise about 6 inches of refractory fiber confined between the plate 13 and the support 15, the support 15 being made in quarter sections and perforated with $\frac{1}{8}$ inch holes on $\frac{1}{4}$ inch staggered centers. Stainless steel bolts 16 secure the basket sections to the plate 13.

The entire unit can be supported at the top of the stack 10 by means of support beams 35 extending between the plate 19 and the re-enforcing ring 36 about the stack. The internal lining 11 within section 10a is retained by the ring 32, there being no necessity for the abrasion-resistant lining 11 in the top section of the member 10a, which as shown in the drawings is integral with the stack 10. How-

ever, it may be desirable to re-enforce the lining 21 on the outer wall of member 10a and we may provide plates 37 fixed to the shell 10a and extending radially beyond the lining 21 for such purpose.

5 Installations such as that described above have proven very satisfactory in service and have solved an otherwise difficult and bothersome noise problem in refinery areas. In any event, from the above it will be apparent that we have devised an acoustic cap which absorbs the entrained 10 sound produced by the throttling valves within a lower portion of the stack 10. Likewise, by the positioning of the sound-absorbing pad 17 at a point substantially above the vent ports 12, we have for all practical purposes eliminated the erosive effect of the entrained solids within 15 the cap.

Although we have described our invention in terms of a single unit at the top of a stack, it is also contemplated that we may arrange a plurality thereof in superposed series. For such purposes, additional ports 12 are provided 20 on the inner wall of the annular chamber 20 to discharge above the cap plate 13 into an extension of the member 10a. Also, an annular sound-absorbing pad, similar to 13-15-17, should be provided at the top of the annular space 20. This modified series arrangement 25 can be repeated as necessary to multiply the effect of the single silencer illustrated in the drawings.

Modifications in the structure and in the mode of operation of the apparatus described herein can be made by those skilled in the art without departing from the invention, and it should be understood that the embodiments described in some detail and shown in the drawings are for the purpose of illustrating the invention without being limited thereto.

What we claim is:

35 1. An acoustic cap for reducing stack noises generated by venting flue gases containing finely divided solids which comprises in combination a sleeve arranged about the upper end of a stack and spaced therefrom to provide an annular chamber, plate means for closing the lower end 40 of the annular chamber between said stack and said sleeve, means for supporting said bottom closure plate means and said sleeve on said stack, a plurality of flue gas ports in the wall of said stack and discharging therefrom into said annular chamber, a cap plate assembly across the upper end of said stack, said assembly including a cap plate, a perforated support fixed below said cap plate, and a quantity of sound absorbing fiber disposed between said perforated support and said cap plate, linings within said sleeve and on the outer surface of said stack comprising abrasive-resistant refractory sound-absorbing means, the distance between said ports in said stack and the stack cap plate assembly with its sound-absorbing fiber being sufficiently great so that entrained solids cannot impinge at their flow velocity on said cap plate assembly, a plurality of pairs of perforated spaced metal plates partitioning the said annular chamber, and an acoustic absorber means between adjacent plates in said pairs, the sub-chambers of the said annular chamber so produced being stream-lined with respect to the flow of flue gases from said ports.

60 2. The structure of claim 1 wherein the total flow area of the ports is at least equivalent to the flow area of said upper end of said stack and wherein said cap plate assembly is placed a distance above said ports of at least 3 feet with a flow rate of exhaust gases into said upper end of said stack of less than about 100 feet per second.

65 3. An acoustic absorber cap for reducing stack noise and enhancing separation of suspended solids with a minimum of erosion which comprises in combination a first tubular member of substantially the diameter of the stack on which it is applied, an acoustic absorber plate means across the upper end of said tubular member, several large vent ports in the wall of said member adjacent only the end thereof remote from said plate, the area of said ports being at least equal to the flow area of the said first tubu-

lar member, an annular bottom closure extending radially from the outer wall of said tubular member at a point below said ports, a second tubular member spaced from said first tubular member and supported by said bottom closure to provide an annular chamber surrounding said tubular member, vent means from said annular chamber disposed at a level above said acoustic absorber plate means and through which flue gases flow from said ports into the atmosphere, and a sound-absorbing lining on the walls and floor of said annular chamber, the annular chamber being divided into a plurality of streamlined, sound-absorbing channels, each such channel communicating with only one of said ports and being of substantially the same cross-sectional flow area as that of each port.

4. The acoustic cap of claim 3 wherein the acoustic absorber plate means includes a perforated support means, a mass of sound-absorbing refractory fiber within said support means, the distance between the ports and said sound-absorbing mass being greater than the distance of travel of the entrained solids which separate from the gases venting through the said ports whereby there is a minimum of impingement of said sound-absorbing plate means by the said solids.

5. An acoustic cap for reducing stack noise wherein fluids containing finally divided solids are vented which comprises an annular plate means disposed about a stack, a cylindrical casing supported by said annular plate means and arranged concentric to the stack to provide an annular chamber, a cap plate means disposed across an upper

10

15

20

25

30

portion of said stack thereby providing a sound-attenuating and solids-separating chamber at the top of said stack, several large flow ports in the wall of said stack discharging into said annular chamber, vent means from said annular chamber discharging at a level above said cap plate means, and sound-absorbing linings within said annular chamber and within said stack, said annular chamber being divided into a plurality of streamlined channels, each communicating with only one of said ports thereby to minimize the level of noise resulting from the venting of the gases through said ports, whereby noise generated within said stack below said cap is substantially absorbed by said absorbing cap plate means and whereby entrained solids are separated from the flowing gases within the said sound-attenuating and solids-separating chamber at the top of said stack.
